UNITED STATES PATENT OFFICE.

FREDERICK STEINKOENIG, OF CINCINNATI, OHIO, ASSIGNOR OF ONE-HALF
TO VALENTINE MARZ, OF SAME PLACE.

DEVICE FOR PREVENTING WATER-PIPES FROM FREEZING.

SPECIFICATION forming part of Letters Patent No. 357,241, dated February 8, 1887.

Application filed November 29, 1886. Serial No. 220,122. (No model.)

To all whom it may concern:

Be it known that I, FREDERICK STEINKOENIG, a citizen of the United States, and a resident of Cincinnati, in the county of Hamilton and State of Ohio, have invented certain new and useful Improved Devices for Preventing Water-Pipes from Freezing, of which the following is a specification.

My invention is an improved means to empty the water-pipes in buildings, and also the branch pipes leading from the street-main, so as to prevent freezing and bursting the pipes.

The invention will be first fully described in connection with the accompanying drawings, and then particularly referred to and pointed out in the claims.

Figure 1 is a central longitudinal section of the device secured in the water-main, the valve 20 being open for the admission of water through the house-pipes. Fig. 2 is an enlarged detail view of the valve in the closed position. Fig. 3 is a similar view of the open valve, but taken at a right-angle to the position shown in Fig. 1.

25 A represents the street-main, B the valve-case screwed into it, and C the branch pipe screwed into the end of the valve-case and leading from the street into the cellar or basement of the building.

30 D is a union connected to the inner or house end of the pipe C, upon the upper branch of which is a short pipe, E, to which the house-supply pipe is to be connected. On the lower branch of the union is a waste-cock, F, through 35 which the water from the house-pipes and branch pipe C is drawn off when desired.

The valve or cock G has openings g, which register with similar openings in the case and permit a flow of water to the house-pipes 40 through pipe C and branch E when the valve is open, as seen in Fig. 1. The valve-stem H is a tube having branches h, connecting with the large end of the valve or cock. The air-passages in these branches h connect through chambers g' in the cock G and holes or air-passages g'', when the valve is closed, with grooves b in the case, so that air passing through the tubular stem will pass into the pipe C through cock G, thus furnishing a vent 45 to allow the pipe to be emptied. A portion 50

of the end of the case B is cut away at b', and the plug G is fitted with a pin, g'', which limits the movement of the plug in either direction, so as to insure the proper registering of the openings g when the cock is open and the registering of the grooves b and air-passages g' when the water in the main is shut off. The short section of pipe h', which passes through the stuffing-box in the union D, is turned off upon the outside and provided with a hand-wheel, I, by which the cock is turned to let on or shut off the water. The pipe C should of course incline downward from the main to the building to insure perfect drainage. It will be seen from the foregoing that the entire system of pipes in a building, as well as the branch from the street-main, may be completely emptied by turning the cock to stop off the water at the main and opening the waste-cock. Thus all danger from freezing is avoided.

The operation of the device is as follows: It being assumed that the supply end of the system of pipes throughout the building is secured upon the branch E and a hose or other pipe connected to the lower branch of the waste-cock F and leading from it to the sewer or other outlet from the cellar of the building, and the cock G turned in the position shown in Figs. 1 and 3, the water passes from the main A through pipe C, branch E, and thence through the system of house-pipes. In extreme cold weather, when there is danger of the water in the house-pipes freezing, the hand-wheel I is turned one-fourth revolution, which is determined by the pin g''. The water is now stopped from the main pipe A to C, and the air admitted through tubular stem H, its branches h, and the slot d back of the water in pipe C. Waste-cock F being opened, the water from pipes C and the system of house-pipes is therefore carried off through the waste-cock and the pipes emptied. To insure the complete emptying of the house-pipes, it is better to open one of the upper faucets in the house, as is now usually done in emptying the house system.

My invention is especially intended to empty the pipe leading from the street-main to the cellar of the house, the freezing of which necessitates the tearing up of the street and pavement.

What I claim as new, and desire to secure by Letters Patent, is—

1. The branch pipe having stop-cock at one end and a union, as D, at the opposite end, with 5 the hollow stem for actuating said cock and passing through said union and branch pipe, whereby the water is turned on or off at the main and air admitted to the cock when closed for the purpose of exhausting the branch pipe, to substantially as specified.

2. The combination, substantially as speci-

fied, of the cock having air and water passages, the hollow stem having branches communicating with the cock when closed, the branch pipe C, having the union D, provided with branch E, and waste-cock F, the several parts combined to operate as and for the purpose set forth. 15

FREDERICK STEINKOENIG.
